Primary Examiner — Karen E Eldridge Powers

(57) **CLAIM**

The ornamental design for a hair straightening brush, as shown and described.

DESCRIPTION

FIG. 1 is a front, bottom and left side perspective view of a hair straightening brush showing my new design; FIG. 2 is a rear, top and right side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of the hair straightening brush wherein the bristle carrier is not shown for clarity of illustration; and, FIG. 10 is an exploded perspective view of the hair straightening brush. The broken lines in the drawings depict portions of the hair straightening brush that form no part of the claimed design.

1 Claim, 10 Drawing Sheets
